CLAIM

(57) The ornamental design for a martial arts stick, as shown and described.

DESCRIPTIONFIG. 1 is a perspective view of martial arts stick;
FIG. 2 is a front elevation view thereof, the rear elevation view
being identical;
FIG. 3 is a left side elevation view thereof, the right side
elevation view being identical;
FIG. 4 is a top plan view thereof; and,
FIG. 5 is a bottom plan view thereof.
The broken line showing of two parallel lines depicts envi-
ronment and forms no part of the claim.**1 Claim, 5 Drawing Sheets**FIG. 1

FIG. 2

FIG. 3

FIG. 4
